(57) **CLAIM**

The ornament design for a pair of sandals, as shown.

DESCRIPTION

FIG. 1 is a perspective view of a pair of sandals, showing my new design;

FIG. 2 is a front view of the right foot sandal, shown removed from the pair for clarity of disclosure;

FIG. 3 is a left side view thereof;

FIG. 4 is a right side view thereof;

FIG. 5 is a rear view thereof;

FIG. 6 is a top view thereof; and,

FIG. 7 is a bottom view of the left foot sandal, shown removed from the pair for clarity of disclosure.

The broken lines illustrate environmental structure and form no part of the claimed design.
